SHAVING APPARATUS

Frederick E. Moskovics, Greenwich, Conn., assignor to Eleanor U. Andrews, Greenwich, Conn.

Application December 1, 1939, Serial No. 307,005

10 Claims. (Cl. 30—43)

This invention relates to shaving devices and more particularly to improvements in the shearing heads or face plates for dry shaving razors of the types having dome-shaped, cylindrical or semi-cylindrical shearing heads.

It has been observed that shearing heads of the type having a series of small apertures therein are unable to pick up and sever long hairs which lie close to or flatly against the skin. Therefore, if hairs are missed during shaving or are allowed to grow because of infrequent shaving, it is extremely difficult thereafter to obtain a clean and complete shave with devices of the character described above.

Inasmuch as it is desirable to provide shaving devices which will operate satisfactorily under all conditions, means should be provided for picking up the long hairs and subjecting them to the action of the cutting elements.

An object of the present invention, accordingly, is to provide improved shear plates for shaving devices which will pick up and cause long hairs to be severed.

Another object of the invention is to provide shaving heads which will assure severance of long hairs or hairs lying flatly in engagement with the skin without decreasing the efficiency of the shaving devices.

Other objects of the invention will become apparent from the following description of typical forms of shaving devices embodying the present invention.

In its broadest aspects, this invention consists of providing dome-shaped, cylindrical or semi-cylindrical shearing heads having a plurality of minute apertures therein with one or more thin bars which lie against the outer surface of the shear plate and act to dislodge and straighten up hairs which lie close to or flatly against the skin. More particularly, these bars should be arranged in such relationship to the shearing head or face plate that no matter at what angle the shearing head is drawn across the skin or what position of the shearing head is relatively to the skin one or more of these bars should engage the skin and thereby lift and project the hairs into the apertures in the shear plate where they may be engaged and severed by the cooperating shearing blade.

These bars preferably are of comparatively small width transversely in order that they will not obstruct too large an area of the shearing head and thus reduce its efficiency during a shaving operation. Inasmuch as the curved type of shearing head presents the maximum area for

engagement with the skin, a plurality of these narrow pick-up bars will not reduce the effective or working area of the shear plate to such a great extent that the shearing action is seriously effected. In fact, the presence of these bars appears to improve the operation of the shaving devices for the reason that they tend to stretch and ripple the skin which tilts the hairs upwardly, projects even the short hairs farther into or through the shear plate and causes them to be severed closer to the surface of the skin. Moreover, the bars have the advantage of reinforcing the shear plate and protecting it against damage.

For a better understanding of the present invention, reference may be had to the accompanying drawing in which:

Figure 1 is a side elevation of a shaving device having a shearing head thereon of a type embodying the present invention;

Figure 2 is a top plan view of a shearing head of the type disclosed in Figure 1;

Figure 3 is a view in section taken on line 3—3 of Figure 2;

Figure 4 is a top plan view of a shaving device having a cylindrical shearing head of the type embodying the invention; and

Figure 5 is a plan view of a modified form of shearing head embodying the invention.

One form of the invention is disclosed in Figures 1 to 3 as applied to the type of shaving device disclosed in the Moskovics and Abrams Patent No. 2,119,021, granted May 31, 1938. This shaving device is characterized by a handle 10 within which is disposed a motor for driving a rotary blade support 11. A plurality of blades 12 are mounted in the blade support 11 and engage the inner surface of a perforated shear plate 13 which is fixed in the end of a tubular sleeve 14 detachably connected to the handle 10. The present invention as applied to this form of shaving device consists in providing, as best shown in Figure 2, a cross-shaped member 15 of thin metal which is fixed to or lies tightly against the outer surface of the perforated shear plate 13. This cross-shaped member 15 preferably is about .010 inch in thickness and thus does not project an appreciable distance from the surface of the shear plate 13. While this member 15 has been shown as cross-shaped, it will be understood that it may be a single bar extending diametrically across the shaving head, or it may have three or more arms or bars which extend radially from the center of the shear plate. The bars 16 of the cross-shaped member 15 preferably are narrow and not greatly exceeding $\frac{1}{16}$

inch in width. Inasmuch as the width of the bars does not affect their ability to pick up the hairs, it is desirable to keep the bars quite narrow to avoid obstructing a large portion of the area of the shear plate 13.

As illustrated in Figure 3, the bars 16 of the member 15 may be slightly undercut at their edges 17 in order to lift and project the hairs into the apertures adjacent thereto. Thus, as the shearing head is passed over the face the bars 16, in all positions of the shearing head, can engage hairs lying flatly against the skin, lift them upwardly slightly and project them into the apertures in the shear plate 13. The ripple formed in the skin by contact with the bars also tends to straighten up the hairs and project them outwardly from the skin. While the bars 16 have been illustrated as undercut, satisfactory operation may be obtained with substantially rectangular bars or bars that have slightly curved outer surfaces. However, the lateral edges of the bars are, in all forms of the invention, substantially perpendicular to the surface of the shear plate 13.

The form of the invention disclosed in Figure 4 is illustrated as applied to a shearing head having a cylindrical or semi-cylindrical skin contacting portion. The shear plate 20 is formed of a curved strip of metal having apertures 21 through which hairs are projected to be severed by a cutter blade 22 disposed interiorly thereof. In order to lift and project long hairs or hairs lying flatly against the skin into the apertures 21, I have provided longitudinally extending bars 23 on the outer surface of the shear plate 20. These bars, like those disclosed in Figures 1 to 3, may be about $\frac{1}{16}$ of an inch in width and about .010 of an inch in thickness. By spacing these bars at about $\frac{1}{4}$ inch intervals along the shear plate 20 they will be able in all positions of the shear plate 20 to pick up and project the hairs through the apertures 21 for severance by the blade 22.

Another form of the invention is disclosed in Figure 5 which is likewise applied to a cylindrical or semi-cylindrical shear plate 30. The shear plate 30 is provided with a plurality of apertures 31 through which hairs may be projected to be severed by a cutting blade disposed interiorly thereof. In this form of the invention the hair-lifting bar 32 extends diagonally or spirally across the outer surface of the shear plate 30 and thus can engage hairs no matter what the position of the shear plate 30 with respect to the skin. Therefore, the bar 32, similarly to the pick-up bars previously described, tends to lift and project the hairs through the apertures 31 where they may be severed by the inner cutter member.

From the foregoing description of typical forms of the invention, it will be apparent that I have provided a simple and effective means for rendering shaving devices of the character described above capable of severing long hairs and hairs which lie flatly against the skin.

It will be understood that many variations in the arrangement of the hair-lifting and guiding bars may be made without departing from the invention so long as the principles underlying this invention are embodied in these variations of the shaving devices. Accordingly, the above embodiments of the invention should be considered as illustrative only and not as limiting the scope of the following claims.

I claim:

1. In a shaving device including an extremely thin skin-contacting shear plate having a plu-

rality of small apertures therein through which hairs may be projected, a cooperating shearing element engageable with one surface of said shear plate and means for moving said shearing element relatively to said shear plate for cooperation with the edges of the apertures to sever hairs projecting through said apertures; the combination with said shear plate of at least one bar extending across a skin-contacting surface of said shear plate having a substantially straight lateral edge substantially perpendicular to said shear plate and positioned immediately adjacent the edges of at least part of said apertures, said lateral edge of said bar being adapted to engage, lift and project hairs through the said apertures adjacent said lateral edge for severance by said shearing element.

2. In a shaving device including an extremely thin skin-contacting shear plate having a plurality of small apertures therein through which hairs may be projected, a cooperating shearing element engageable with one surface of said shear plate and means for moving said shearing element relatively to said shear plate for cooperation with the edges of the apertures to sever hairs projecting through said apertures; the combination with said shear plate of at least one bar about .010 of an inch in thickness extending across a skin-contacting surface of said shear plate having a substantially straight lateral edge substantially perpendicular to said shear plate and positioned immediately adjacent the edges of at least part of said apertures, said lateral edge of said bar being adapted to engage, lift and project hairs through the said apertures adjacent said lateral edge for severance by said shearing element.

3. In a shaving device including an extremely thin skin-contacting shear plate having a plurality of small apertures through which hairs may be projected, a cooperating shearing element engageable with the inner surface of said shear plate and means for moving said shearing element relatively to said shear plate for cooperation with the edges of the apertures to sever hairs projecting through said apertures; the combination with said shear plate of a pair of thin bars extending across the skin-contacting surface of said shear plate and disposed at an angle to each other, each bar having at least one lateral edge substantially perpendicular to said shear plate, and positioned immediately adjacent the edges of at least part of said apertures, the said lateral edge of each bar being adapted to engage, lift and project hairs into apertures adjacent to said edge for severance by said shearing element.

4. In a shaving device including an extremely thin skin-contacting shear plate having a plurality of small apertures through which hairs may be projected, a cooperating shearing element engageable with the inner surface of said shear plate and means for moving said shearing element relatively to said shear plate for cooperation with the edges of the apertures to sever hairs projecting through said apertures; the combination with said shear plate of a pair of bars about .010 of an inch in thickness extending across the skin-contacting surface of said shear plate and disposed at an angle to each other, each bar having at least one lateral edge substantially perpendicular to said shear plate and positioned immediately adjacent the edges of at least part of said apertures, the said lateral edge of each bar being adapted to engage, lift

and project hairs into apertures adjacent to said edge for severance by said shearing element.

5. In a shaving device including a thin, substantially circular, convex, skin-contacting shear plate having small apertures therein through which hairs may be projected, a shearing element engageable with the inner surface of said shear plate and means for moving said shearing element relatively to said shear plate for cooperation with the edges of the apertures to sever hairs projecting through said apertures; the combination with said shear plate of a plurality of thin bars extending radially across and engaging the skin-contacting surface of said shear plate, each bar having a substantially straight lateral edge substantially perpendicular to said shear plate and positioned immediately adjacent the edges of at least part of said apertures, the said lateral edge of each bar being adapted for engaging and projecting hairs into the said apertures adjacent the bars for severance by said shearing elements.

6. In a shaving device including a thin, substantially circular, convex, skin-contacting shear plate having small apertures therein through which hairs may be projected, a shearing element engageable with the inner surface of said shear plate and means for moving said shearing element relatively to said shear plate for cooperation with the edges of the apertures to sever hairs projecting through said apertures; the combination with said shear plate of a plurality of bars about .010 of an inch in thickness extending radially across and engaging the skin-contacting surface of said shear plate, each bar having a substantially straight lateral edge substantially perpendicular to said shear plate and positioned immediately adjacent the edges of at least part of said apertures, the said lateral edge of each bar being adapted for engaging and projecting hairs into the said apertures adjacent the bars for severance by said shearing elements.

7. In a shaving device including a shear plate having a thin semi-cylindrical skin-contacting portion provided with apertures through which hairs may be projected, a shearing element within and engageable with the inner surface of said shear plate and means for moving said shearing element relatively to said shear plate for cooperation with the edges of the apertures for severing hairs projected through said apertures; the combination with said shear plate of a plurality of thin substantially parallel bars extending longitudinally of and in engagement with the outer surface of said cylindrical portion, each bar having at least one substantially straight lateral edge substantially perpendicular to the skin-contacting portion and positioned immediately adjacent the edges of at least part of said apertures, the said lateral edge of each bar being adapted for engaging and projecting hairs through said immediately adjacent apertures for severance by said shearing element.

8. In a shaving device including a shear plate

having a thin semi-cylindrical skin-contacting portion provided with apertures through which hairs may be projected, a shearing element within and engageable with the inner surface of said shear plate and means for moving said shearing element relatively to said shear plate for cooperation with the edges of the apertures for severing hairs projected through said apertures; the combination with said shear plate of a thin bar extending spirally across the outer surface of and having at least one lateral edge perpendicular to said semi-cylindrical portion and positioned immediately adjacent the edges of at least part of said apertures, the said lateral edge of said bar being adapted for engaging and projecting hairs through said immediately adjacent apertures for severance by said shearing element.

9. In a shaving device including a head member provided with an extremely thin skin-contacting shear plate having a plurality of small apertures through which hairs may be projected, a cooperating shearing element engageable with the inner surface of said shear plate and means for moving said shearing element relatively to said shear plate for cooperation with the edges of the apertures to sever hairs projecting through said apertures; the combination with said shear plate of hair lifting means comprising a plurality of thin bars extending in the form of a spider across the skin-contacting surface of said shear plate and anchored at the ends thereof to said head member, and each of said bars having at least one lateral edge substantially perpendicular to said shear plate and positioned immediately adjacent the edges of at least part of said apertures, the said lateral edge of each bar being adapted to engage, lift and project hairs into said immediately adjacent apertures of said plate for severance by said shearing element.

10. In a shaving device including a cylindrical sleeve, a thin, convex, skin-contacting shear plate supported by the end of said sleeve, said plate being provided with a plurality of small apertures therein through which hairs may be projected, a cooperating shearing element engageable with the inner surface of said shear plate and means for moving said shearing element relatively to said shear plate for cooperation with the edges of the apertures to sever hairs projecting through said apertures; the combination with said shear plate of hair lifting means comprising a plurality of thin bars extending radially from the center portion of said shear plate and having the ends thereof anchored to said sleeve, each of said bars having a lateral edge substantially perpendicular to the skin-contacting surface of said shear plate and positioned immediately adjacent the edges of at least part of said apertures, the said lateral edge of each bar being adapted for engaging and projecting hairs through said plate for severance by said shearing element.
